UNITED STATES PATENT OFFICE.

FRANK M. KAUFMAN, OF PHILADELPHIA, PENNSYLVANIA.

DESIGN FOR A TEXTILE FABRIC.

Application filed December 4, 1924. Serial No. 11,581. Term of patent 3½ years.

To all whom it may concern:

Be it known that I, FRANK M. KAUFMAN, a citizen of the United States, residing at Philadelphia, in the county of Philadelphia and State of Pennsylvania, have invented a new, original, and ornamental Design for Textile Fabrics, of which the following is a specification, reference being had to the accompanying drawing, forming a part thereof.

The figure is a face view of a textile fabric, showing my new design.

I claim:

The ornamental design for a textile fabric, as shown.

FRANK M. KAUFMAN.
